[57] **CLAIM**

The ornamental design for a holddown and retaining device component, as shown and described.

DESCRIPTION

FIG. 1 is a front elevational view of a holddown and retaining device component showing my new design with the broken lines for illustrative purposes only.
FIG. 2 is a view thereof as seen from the top of FIG. 4.
FIG. 3 is a side view thereof taken from the left of FIG. 4.

FIG. 4 is a rear elevational view thereof.
FIG. 5 is a side view thereof taken from the right of FIG. 4.
FIG. 6 is a bottom view thereof.
